UNITED STATES PATENT OFFICE.

ISADOR E. LOEWENBERG, OF CONVERSE, INDIANA.

DESIGN FOR A CLOTHES-HAMPER.

55,289.

Specification for Design.

Patented May 25, 1920.

Application filed October 9, 1919. Serial No. 329,617. Term of patent 7 years.

To all whom it may concern:

Be it known that I, ISADOR E. LOEWENBERG, a citizen of the United States, residing at Converse, in the county of Miami and State of Indiana, have invented a new, original, and ornamental Design for Clothes-Hampers, of which the following is a specification, reference being had to the accompanying drawing, forming part thereof.

Fig. 2 is an enlarged top plan view of the cover of a clothes hamper.

I claim:

The ornamental design for a clothes hamper, as shown.

ISADOR E. LOEWENBERG.
